UNITED STATES PATENT OFFICE

LOUIS V. ARONSON, OF NEWARK, NEW JERSEY, ASSIGNOR TO ART METAL WORKS, INC., A CORPORATION OF NEW JERSEY

CASING NOZZLE

Original application filed September 13, 1929, Serial No. 392,426. Divided and this application filed February 3, 1930. Serial No. 425,395.

My invention relates to a casing, receptacle, container or the like hereinafter generally termed a "casing" and adapted to contain a suitable substance or material, as fuel which may be semi-solid, jelly-like or of viscous consistency.

My invention relates to a casing, as aforesaid, having a nozzle of novel characteristics adapting it for readily detachable association with a pyrophoric lighter casing.

Further advantages, objects and characteristics of my invention will become apparent from the following detailed description taken in connection with the accompanying drawings.

My invention resides in the casing, nozzle features, and in the combination of parts and features of construction of the character hereinafter described and claimed.

This application is a division of my application Serial No. 392,426, filed September 13, 1929.

For an understanding of my invention, reference is to be had to the accompanying drawings, in which:

Figure 1 is an elevational view of a fuel-containing casing as constructed in accordance with my invention;

Figure 2 is an elevational view, partly broken away, and shows the fuel-containing casing detachably associated with a pyrophoric lighter casing;

Figure 3 is an enlarged elevational view, partly in section, of a part of the arrangement shown in Figures 2 and 4; and

Figure 4 is an elevational view, partly broken away, and shows the fuel-containing casing after a quantity of fuel has been removed therefrom.

For purposes of explanation and to illustrate an important application of my invention, I have shown on the accompanying drawings an arrangement for introducing semi-solid or jelly-like fuel interiorly of the casing of pyrophoric lighting mechanism L which may be of any suitable or desired character or type. As illustrative of one of the many forms of lighting mechanism to which my invention is applicable, I have shown the aforesaid lighting mechanism L

as comprising a casing 1 having a top wall 2 and a bottom wall 3. Projecting from the top casing wall 2 is the flame-producing mechanism per se which may be of any suitable type. As shown such mechanism comprises a member 4 reciprocatory, by manual action, to swing a lever 5 on a shaft or member 6 carried by spaced standards projecting from said top casing wall. The lever 5 carries the usual snuffer cap which forms a movable housing for the end of a wick tube 7 extending through the top wall of the casing 1. As is usual, a wick 8 disposed interiorly of said casing 1 extends through the wick tube 7 and projects slightly therebeyond. When the member 4 is moved toward the top casing wall 2, suitable spark-producing members, not shown, co-act to produce a shower of sparks which are directed toward the end of wick 8, the latter being exposed at this time due to movement therefrom of the aforesaid snuffer cap in response to pivotal movement of lever 5 as effected by the last described movement of member 4.

As is usual in the art, the casing 1 constitutes a reservoir or receptacle for fuel which heretofore, usually, has been liquid in character, as benzine, gasoline, or the like. For introducing such fuel into the casing 1, it has been customary to provide an opening or perforation 9 in the bottom casing wall 3, said opening being constituted by a sleeve-like extension, if desired, and being interiorly threaded for engagement with the exterior threads of a closure cap or plug 10. When the cap 10 is removed, a supply of fuel may be introduced into the casing 1 which may or may not, as desired, contain a body of suitable material for absorbing the fuel.

In lieu of the aforesaid liquid fuel and in accordance with my invention, there is utilized and introduced into the casing 1, or any other similar or desired casing, semi-solid or jelly-like fuel of any suitable character such, for example, as described in the co-pending application of Nathan Proper, Serial No. 342,306, filed February 23, 1929.

Semi-solid or jelly-like fuel of the character described above may be dispensed or

sold on the market in a casing or tube T which, in the example illustrated, comprises a fuel containing section or body portion the wall structure of which is deformable sheet-like metallic material closed or sealed at one end and, at the other end, comprising a sleeve-like extension or spout a serving as a nozzle or orifice having an opening of suitable extent for the passage therethrough of the semi-solid or jelly-like fuel upon application of pressure to said wall structure.

In accordance with my invention, the extension or spout a is of conical configuration converging in a direction leading from the body section of tube T and is formed of suitable impressionable material, as soft metal, and, throughout a great or the major length thereof, comprises a substantially smooth or even exterior surface. Immediately adjacent the end of said spout or nozzle a, suitable threads b may be provided for the reception of a closure cap c.

With the closure cap c threaded to the nozzle a, the fuel-containing tube T is dispensed or sold on the market in the condition illustrated in Figure 1. When the purchaser of such a tube T desires to refill or restock the casing of his lighting mechanism with fuel, the closure cap 10 of the latter is removed and the closure cap c of the tube T is likewise removed. Thereupon, the nozzle a of tube T may be inserted into the filling opening of the lighter casing and by suitably applied pressure axially of said tube T, while simultaneously rotating the same, one or more threads d are formed on the spout a by die-like action of the interior threads of the opening a whereby the tube T is so held in assembled relation to the casing of the pyrophoric lighting mechanism that pressure upon the wall structure of said tube T forces fuel through the nozzle a into the lighting mechanism casing to charge the latter with a supply of fuel F, Figure 4.

After a suitable supply of fuel has been introduced into said last named casing, the tube T, by reverse rotation, may be unthreaded therefrom whereupon the respective closure caps may be placed in position, the cap 10 being threaded into the lighting mechanism casing and the closure cap c being threaded to the threads b of spout a. The tube T may now be laid away until it is again desired to refuel the lighting mechanism whereupon the operation described above may be repeated, the previously formed threads d again serving to unite the two casings.

As hereinbefore stated, the spout a, preferably, has an exterior conical configuration and it is desirable that the inclination of the cone elements be relatively sharply inclined with respect to the cone axis. This arrangement is preferable because the spout a is thereby adapted to be associated with any

one of a plurality of casing filling openings, even though such filling openings may have substantially different diameters, as those of different makes, models or styles, those of larger diameter, obviously, co-acting with and threading the spout a nearer the base of the cone and those of smaller diameter co-acting with and threading said spout a somewhat nearer the apex of the cone.

An added advantage of my invention resides in the fact that a single spout a may be adapted to be associated with a plurality of lighter casings even though the fuel openings thereof have different diameters. This follows because the fuel opening of a certain diameter causes the formation of threads in one region along the spout a, and the filling opening of another diameter causes the formation of other threads in another region therealong.

By the above described manner of assembling the casings T and L, a tight joint is obtained and, therefore, leakage or wastage of fuel is obviated when transfer is effected from one casing to the other. The fuel comes into the casing L under pressure, the displaced air passing to the atmosphere by way of the wick tube 7. To some extent, this action results in the transfer of fuel to the immediate vicinity of the wick 8 which absorbs the fuel in the lighter mechanism casing and causes the transfer of inflammable material to the region of combustion.

Although illustrated particularly in connection with the refueling of the casings of lighting mechanism, it shall be understood that my invention is useful in other relations for effecting the transfer of material other than fuel in either direction from one casing to another when they are connected in accordance with my invention.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claim to cover all such changes and modifications.

What is claimed as new and desired to be secured by Letters Patent is:

A casing having a body section and a nozzle, threads on said nozzle for a closure cap, said nozzle adjacent the tip thereof comprising an unthreaded conical section of soft metal adapted to be externally threaded by the die-like action of the internally threaded filling opening of a pyrophoric lighter casing.

In testimony whereof I have signed my name to this specification.

LOUIS V. ARONSON. 130
